UNITED STATES PATENT OFFICE

HARVEY S. PARK, OF CHICAGO, ILLINOIS, ASSIGNOR TO THE WESTINGHOUSE AIR BRAKE COMPANY, OF PITTSBURG, PENNSYLVANIA.

AIR-BRAKE.

SPECIFICATION forming part of Letters Patent No. 610,947, dated September 20, 1898.

Application filed March 7, 1890. Serial No. 343,046. (No model.)

To all whom it may concern:

Be it known that I, HARVEY S. PARK, a citizen of the United States, residing at Chicago, in the county of Cook and State of Illinois, have invented certain new and useful Improvements in Air-Brakes; and I do hereby declare that the following is a full, clear, and exact description of the invention, which will enable others skilled in the art to which it pertains to make and use the same, reference being had to the accompanying drawings, in which—

Figure 1 is a sectional elevation showing the main valve, a portion of the brake-cylinder, a portion of the train-pipe, a vent-valve for the train-pipe, and a valve for admitting train-pipe pressure direct to the brake-cylinder, and showing also an electrical appliance for actuating the valve which admits the direct train-pipe pressure. Fig. 2 is a top or plan view of the valve with the cap or cover removed. Fig. 3 is a sectional elevation showing the main valve and a portion of the pipe connecting the main valve with the car-reservoir. Fig. 4 is a detail showing the slide-valve of the main-valve mechanism. Fig. 5 is a face view of the main-valve chamber, showing the ports and passages therein.

This invention relates to air-brakes of that class in which a main valve, a car-reservoir, and a brake-cylinder, with a train-pipe communicating with the main valve, are used on each car of the train and controlled by the engineer, and has for its object to insure the application of the brakes throughout the entire train simultaneously, and thereby prevent the non-setting of the brakes on a long train, as is apt to be the case where the engineer's valve alone is used as the vent for the entire train-pipe, to improve the construction and operation of the main valve and its coacting devices, and to improve generally the construction and arrangement of the mechanism constituting the valve as a whole; and its nature consists in the several parts and combinations of parts hereinafter described, and pointed out in the claims as new.

In the drawings, A represents the train-pipe.

B is a cap or cover for the main-valve chamber at the train-pipe end thereof.

C is a chamber in the cap or cover B, into which chamber the end of the train-pipe A enters and has communication therewith.

D is a passage leading from the chamber C. 55

E is the shell or casing of the triple-valve device, to the end of which is secured by suitable bolts the cap or cover B, and between the face of the cap or cover B and the end face of the casing E is a suitable packing to 60 make an air-tight joint.

F is the main-valve piston-chamber within the casing E.

G is a plate or disk, and G' is a companion plate or disk, and, as shown, the plate or disk 65 G at its center has a stem X, around which is a coiled spring X', one end of which abuts against the face of the plate or disk G and the other rests upon a plate y, supported on a pin y', and this plate y lies within a chamber z, formed in the cap B, which chamber z has a continuation z' for the entrance of the stem X in the backward movement of the piston. 70

H are cup-leather packings located between 75 the plates or disks G and G' and extending one over each edge of the respective plates or disks, as shown in Fig. 1.

I is a stem formed with or suitably secured to the plate or disk G'. The piston formed 80 by the disks G G' and cup-leather packing H is located in the chamber F, and the chamber F communicates with the chamber C by a port a and a chamber b, and the port a is controlled by a valve c, located in the chamber 85 B and having a stem d passing through the port a, with a pin d' at the end of the stem to hold the valve against being moved too far, and the valve c has a small hole e, which acts as a vent and allows a communication between 90 the chamber C and the chamber F when the valve c is seated.

J is a head on the end of the stem I, which head when the piston is in its normal position abuts against the cap or cover of the cylinder E, as shown in Fig. 1. The end of the stem I, adjacent to the head J, has a chamber f, and through the head J is a hole f', leading from the chamber f. A valve g is located in the chamber f and has a stem g' on 100 both sides, and around the stem g' is located a coiled spring g'', one end of which is against

the valve *g* and the other rests upon the bottom of the chamber *f*.

K is a cap or cover for the end of the casing *E* and forming also a head for the brake-cylinder. The cap or cover *K* is attached to the casing by suitable bolts *o*, and the joint between the cap and the casing is made air-tight by a suitable packing *o'*.

L is a slide-valve in the main-valve chamber *F'*, attached to an arm *L'*, extending out from the stem *I* and held to its seat by a coiled spring *h* around the stem or arm *L'*.

M is a passage in the wall of the casing *E* adjacent to the valve *L*, as shown by the dotted lines in Figs. 1 and 5, and this passage communicates with the chamber *F'* by a port *j* and also has a port *k* at its end leading into the chamber *F'*, and through the valve *L* is a port *i*, by which communication is established through the valve *L* with the passage *M* when the port *i* communicates with the port *j*. The face of the valve *L* has a passage *l*, which communicates with the port *k* when the valve is in its normal position and with a passage *m* in the wall of the casing *E*, which passage communicates with a port *n*, leading to the atmosphere.

N is a passage through the cap *K*, in line with the passage *M* in the casing *E*.

O is the brake-cylinder.

P is a passage in the cap or cover *K*, communicating with the chamber *F'* by a port *p*, and into this passage *P* the end of a pipe *P'* leads, which pipe at its other end communicates with a car-reservoir, (not shown,) so that air can pass from the chamber *F'* through the port *p*, passage *P*, and pipe *P'* into the car-reservoir, or air can pass from the car-reservoir in the same manner into the chamber *F'*.

Q are ears projecting out from the cap or head *K*, and *Q'* are corresponding ears projecting out from the brake-cylinder *O*, and through these ears bolts *q* pass, attaching the brake-cylinder *O* to the cap or head *K*, and the joint between the two is made air-tight by a packing *q'*.

R is a chamber in the cap or cover *B*, which communicates with the chamber *C* by the passage *D* and is closed at its end by a screw-threaded plug *R'*, in which is a hole or passage *w*. The chamber *R* also communicates with the main-valve piston-chamber *F* by a passage *r'*, which passage also communicates with a passage *r* in the casing *E*, and this passage *r* communicates with the chamber *F* by a port *s*, and communication is had with the chamber *F*, when the valve *L* is in its normal position, by a port *t* through the valve *L*, which port *t* is closed by a valve *u*, and the valve *u* is held to its seat by a spring *u'*, both the valve *u* and the spring *u'* being attached to the valve *L* by a screw *u''* or in any other suitable manner.

S is a piston in the chamber *R*, which piston has a suitable packing *x* and is provided with a stem *v'*, on which is a valve *v*, which

seats in the opening *w*, and the valve is held to its seat by a spring *x'*, located between the piston *S* and the end wall of the chamber *R*. 70

T is a projection or wall separating the chambers *C* and *R* and in which is located the chambers *z* and *z'*.

U is a chamber formed by an extension *U'* of the casing *E*, and this chamber has communication with the passage *r* in the casing *E*. 75

V is a plate over the end of the chamber *U*.

W is a passage through the cap or head *K*, furnishing a communication between the chamber *U* and the brake-cylinder *O*. 80

The chamber *U* has located therein a plate or disk *4*, having a stem *5*, on which is a disk *6*, and between the disks *4* and *6* is a cup-leather packing *7*, forming, in connection with the disks, a piston. The stem *5* at its 85 end has secured thereto a valve *8*, with a packing *9*, which seats upon a rib *10* on the face of the plate *V*, and this stem passes through a ring *11*, connected with the plate *V* by arms *12*, so as to leave open spaces between the 90 arms around the ring, and between the plate *V* and the disk *6* is a coiled spring *13*, by which the valve *8* is held to its seat in its normal condition. The chamber *U* communicates with the passage *r* by a port *14*, and 95 from the passage *r* a passage *15* leads, which passage communicates with a chamber *16* in the end of a plug *21*, screw-threaded into the end of the wall *U'*, and this chamber *16* has located therein a valve *17* on a stem *18*, which 100 valve closes a port *19*, communicating with passages *20* in the plug *21*, which passages communicate with a passage *22*, leading into the chamber *U* through the wall *U'*. The plug *21* has a chamber *25*, in which is located 105 a stationary armature *23*, having a passage *24* in line with the port *19* and through which passage the stem *18* extends, and in this chamber *25* of the plug *21* is also located a movable armature *26*, by means of which the stem *18* 110 can be moved to raise the valve *17* from its seat. The end of the plug *21* has a cap *27*, in which is a port or opening *28*, leading to the atmosphere, and as the armature *26* leaves a space around it in the chamber *25* air can 115 pass out through the opening *28*. The plug *21* is wound with wire *29*, so as to form a magnet for the armatures *23* and *26*.

The stem *I* is held from turning by arms *1*, having square ends *2*, which enter recesses *3*, 120 formed in the wall of the chamber *F'*, as shown in Fig. 3.

The car-reservoir is charged from the train-pipe by air passing into the chamber *C*, thence through the port *a*, opening the valve *c*, into the chamber *B*, and into the chamber *F*, with the piston in such chamber in its normal position, as shown in Fig. 1, and the air passes from the chamber *F* into the opening or passage *r'* to enter the passage *r*, and from such passage the air will pass through the port *s* and port *t*, opening the valve *u*, entering the chamber *F'* above the piston in such chamber, and passing out through the port *p*, passage 130

P, and pipe P' into the car-reservoir, and such flow of the air will continue until the pressure in the car-reservoir and the pressure in the train-pipe are equal, or nearly so, and 5 when the car-reservoir is charged the apparatus is ready for use.

In use the lowering of the train-pipe pressure reduces the pressure in the chamber F back of the piston in such chamber, and the 10 car-reservoir pressure which is in the chamber F' in front of the piston being in excess will force the piston back, receding the valve L for the port i in the valve L to come in line with the port j, leading into the passage M, 15 when the car-reservoir pressure will flow through the pipe P', passage P, and port p into the chamber F', and thence through the ports i and j into the passage M and through the passage M into the brake-cylinder, setting 20 the brakes with a grading pressure when the reduction in the train-pipe is a few pounds only. An increase of the train-pipe pressure entering the chamber C will raise the valve c for the pressure to pass through 25 the port a and chamber b into the chamber F back of the piston in such chamber, returning the piston to its normal position, as shown in Fig. 1, and such return of the piston returns the valve L to the position shown 30 in Fig. 1 for the port k to be in communication with the passage l and allow air from the brake-cylinder to flow out through the passage N and passage M, port k, passage l, port m, and port n into the atmosphere to release 35 the brakes, and if it is desired to return the piston only partially and retain a grading pressure on the brakes a slight increase in the train-pipe pressure will advance the piston in the chamber F against the resistance 40 of the spring g'', which spring, by reason of the abutment of the stem g' against the face of the head K, will hold the valve L in position for the port i to be out of line with the port j and for the passage l not to be in communication 45 with the port k, the result being a retention of the pressure in the brake-cylinder by which the brakes will be held at the grading pressure, and if such pressure is not sufficient a slight reduction is again made in 50 the train-pipe pressure, repeating the operation first described, by which additional pressure is admitted into the brake-cylinder to set the brakes more firmly.

The reduction of pressure in the train-pipe 55 for the purpose of applying the brakes may be made in the usual way by means of the engineer's valve. This causes a reduction of pressure in the chamber C, passage D, and in chamber R to the right of piston S. The 60 valve c will then be seated, and as the port e through valve c is too small to permit an equalization of the pressures in chambers F and C the pressure in chamber F will move the piston S to the right and open the release-valve v, thereby permitting the air below the piston G to escape to the atmosphere, so that the reservoir-pressure above the piston G

will move said piston down and cause the application of the brakes.

The brakes can be set to the full pressure 70 in case the valve L or its operating devices are inoperative by means of the electrical appliances attached to the wall U', and by these appliances a current can be sent into the magnet by which the armature 26 will be advanced, raising the valve 17 from its seat for air to enter the passage 15 from the passage r and enter the chamber 16 and pass out through the port 19 and passages 20 into the passage 22 to enter the chamber U back of 75 the piston in such chamber, equalizing the pressure on both sides of such piston for the train-pipe pressure entering the chamber U at the port 14 to act on the valve 9 and raise it from its seat, permitting train-pipe pressure to flow through the openings 12 into the brake-cylinder to set the brakes, and this operation of setting the brakes is entirely distinct and separate from the operation of the slide-valve L; but, if desired, both devices 80 can be brought into use, in which case car-reservoir pressure will enter the brake-cylinder through the passages M and N, and train-pipe pressure will enter the brake-cylinder through the chamber U and passage W. 85

A graduated application of the brakes may be effected by a moderate reduction of train-pipe pressure, which is not sufficient to cause the unseating of the valve v. When such moderate reduction of train-pipe pressure is 90 made, the valve c will be seated and the fluid in the chamber F below the piston G will flow through the passage e into the train-pipe, thereby reducing the pressure below the piston G sufficiently to permit the auxiliary-reservoir pressure to move the piston G and the valve L into position for a service application of the brakes. Fluid from the auxiliary reservoir will then flow through the passage i in the valve L and through the passages M and 95 N into the brake-cylinder. 100

When a sufficiently great and rapid reduction of train-pipe pressure is made, the valve c will at first be seated, and the pressure in chamber R to the left of piston S will move 105 the piston S to the right and unseat the valve v. The fluid in chamber F below the piston G will be suddenly exhausted to the atmosphere, and the valve c will be lifted from its seat by the pressure of the fluid in chamber 110 C. Fluid from the train-pipe will flow into the chamber F through the passage a and into chamber R through the passage r', and a portion of the train-pipe fluid may thus escape through the port w to the atmosphere; 115 but whether it does or not the flow of fluid from the train-pipe into the chambers F and R through passages a and r' will cause a reduction of train-pipe pressure in addition to that effected by means of the engineer's 120 valve, and this additional reduction of train-pipe pressure occurring at one triple valve will cause the opening of the valve v at the 125 next succeeding triple valve and successive 130

reductions of train-pipe pressure throughout the train.

The valve v is seated after being withdrawn as the pressure in the chamber R is reduced 5 by passing out through the opening w , and such reduction allows the spring x' to act and force the piston forward, setting the valve v , and the valve is held seated by an increase of the train-pipe pressure, which enters the 10 chamber C and flows through the passage D into the chamber R back of the piston S , and such pressure, in connection with the spring x' , seats the valve and firmly closes the opening or passage w against the outflow of air 15 from the chamber F .

It will be seen that with this construction of valve a nearly simultaneous reduction of the train-pipe pressure for all of the valves is had, as each preceding valve forms a relief- 20 valve for the pressure of the succeeding valve, so that with the reduction at the first valve a corresponding reduction is had for the next valve at the same time, or nearly so, and such reduction extends throughout the entire 25 train, the result being a simultaneous setting of the brakes on the front and rear cars, by which the bumping or coming together of the cars suddenly is entirely obviated and overcome, and consequently no jar or concussion 30 is had on any of the cars in setting the brakes, and this result will be the same whether the brakes are set at a grading pressure or for an emergency stop, and by using independently-operating electrical and air devices for ad- 35 mitting pressure to the brake-cylinder the brakes can be set by the use of either device, or by both devices combined, without any interference of one device with the other.

What I claim as new, and desire to secure 40 by Letters Patent, is—

1. The combination in an air-brake mechanism, of a train-pipe, a port leading from the train-pipe into the main-valve piston-chamber, a valve having a vent-passage and con- 45 trolling said port, a vent-chamber communicat- 50 ing with the train-pipe, a passage from the main-valve piston-chamber to the vent-chamber, a piston in the vent-chamber, and a valve operated by the piston and controlling a vent- 55 passage from the vent-chamber, substantially as set forth.

2. The combination in an air-brake mechanism of a main-valve piston-chamber, a piston in such chamber, a slide-valve carried by 55 the piston and controlling the grading-port, a chamber communicating with the train-pipe, a port between such chamber and the main-valve piston-chamber, a valve with a vent-hole controlling such port, a vent-cham- 60 ber communicating with the main-valve piston-chamber and the train-pipe chamber, a piston in the vent-chamber, a valve carried by the piston, and a vent-opening controlled by the valve, substantially as and for the pur- 65 pose specified.

3. The combination in an air-brake mechanism of a train-pipe chamber, a port from

said chamber to the main-valve piston-chamber, a vented valve controlling such port, a vent-chamber communicating with the train-pipe chamber and the main-valve piston-chamber, a piston in the vent-chamber, a valve carried by the piston, a vent-opening controlled by the valve, and a spring for advancing the piston, substantially as and for the 75 purpose specified.

4. The combination in an air-brake mechanism of a train-pipe, a chamber communicating with the train-pipe, a main-valve chamber, a port between the train-pipe chamber 80 and the main-valve chamber, a valve controlling such port, a passage leading from the main-valve chamber, a passage communicating with the passage from the main-valve chamber and with a secondary chamber, a 85 piston in said secondary chamber carrying a valve controlling a passage leading to the brake-cylinder, a passage leading from the connecting passage of the main-valve chamber and the secondary chamber into the sec- 90 ondary chamber back of the piston, and a valve electrically operated, for admitting train-pipe pressure to the brake-cylinder direct, substantially as and for the purpose 95 specified.

5. The combination in an air-brake mechanism of a main-valve chamber, a passage leading from the main-valve chamber to a vent-chamber, a vent-chamber, a piston in the vent-chamber, a valve carried by the piston, a vent-opening controlled by the valve, a passage leading to a secondary chamber from the main-valve chamber, a piston in the secondary chamber, a valve carried by the piston and controlling the passage leading to the brake- 105 cylinder, a passage leading to the secondary chamber back of the piston, and a valve electrically operated for controlling such passage, for admitting train-pipe pressure direct to the 110 brake-cylinder, substantially as specified.

6. The chamber F , passage r' and passage r , in combination with the chamber U , having a piston therein, valve 8 , controlling the release of fluid from the train-pipe passage 15, and valve 17 , electrically controlled, substan- 115 tially as and for the purposes specified.

7. The train-pipe A , chamber C , passage D , chamber F and vent-chamber R , in combination with the passage r' , passage r , chamber U , having a piston therein, valve 8 , controlling the release of fluid from the train-pipe passage 15, and valve 17 , electrically controlled, substantially as and for the purposes specified.

8. The chamber U having a piston therein, valve 8 , controlling the release of fluid from the train-pipe passage r and port 14 , in combination with the passage 15 , valve 17 , electrically controlled, port 19 , passage 20 , and passage 22 , substantially as and for the pur- 125 poses specified.

9. The chamber U having a piston therein, valve 8 , controlling the release of fluid from the train-pipe port 14 , and passage r , in com-

bination with the passage 15, chamber 16, valve 17 with stem 18, port 19, passage 20, plug 21, and passage 22, substantially as and for the purposes specified.

5 10. The chamber U, having a piston therein, valve 8, controlling the release of fluid from the train-pipe port 14, and passage r, in combination with the passage 15, chamber 16, valve 17 with stem 18, port 19, passage 20,

plug 21, passage 22, stationary armature 23, to passage 24, chamber 25, and movable armature 26, substantially as and for the purposes specified.
